UNITED STATES PATENT OFFICE.

JOSEPH JOHNSON, OF NEW YORK, N. Y., ASSIGNOR TO INDIVIDUAL DRINKING CUP COMPANY, INC., OF EASTON, PENNSYLVANIA, A CORPORATION OF PENNSYLVANIA.

DESIGN FOR A PAPER CUP OR SIMILAR ARTICLE.

Application filed December 19, 1927. Serial No. 24,545. Term of patent 14 years.

To all whom it may concern:

Be it known that I, JOSEPH JOHNSON, a citizen of the United States, residing at New York, in the county of New York, and State of New York, have invented a new, original, and ornamental Design for a Paper Cup or Similar Article, of which the following is a specification, reference being had to the accompanying drawing, forming a part thereof.

In the drawings:

Figs. 1, 2 and 3 show side elevations at different points in the circumference of the cup showing my new design.

I claim:

The ornamental design for a paper cup or similar article, as shown.

JOSEPH JOHNSON.
